(57) **CLAIM**

The ornamental design for a motor vehicle steering wheel, as shown and described.

DESCRIPTION

FIG. 1 is a right, front perspective view of a motor vehicle steering wheel showing my new design;

FIG. 2 is a left, front perspective view thereof;

FIG. 3 is a front view thereof;

FIG. 4 is a rear view thereof;

FIG. 5 is a top view thereof; and,

FIG. 6 is a left side view thereof.

The broken lines in the drawings illustrate portions of the motor vehicle steering wheel that form no part of the claimed design.
